UNITED STATES PATENT OFFICE.

DAVID W. PAYNE, OF ELMIRA, NEW YORK, ASSIGNOR TO SARAH KATE PAYNE, OF ELMIRA, NEW YORK.

ENGINE-GOVERNOR.

SPECIFICATION forming part of Letters Patent No. 735,408, dated August 4, 1903.

Application filed October 25, 1901. Serial No. 79,938. (No model.)

To all whom it may concern:

Be it known that I, DAVID W. PAYNE, a citizen of the United States, residing at Elmira, in the county of Chemung and State of New York, have invented certain new and useful Improvements in Engine-Governors, of which the following is a specification.

My invention relates to centrifugal governors or regulators for steam or other fluid pressure engines of that class which are affixed to the fly-wheel or crank-shaft of the engine or to a shaft rotated thereby and which effect the regulation of the engine-valve by varying the position of a loose or adjustable eccentric or eccentric-pin to which the valve-rod is connected; and the invention relates more particularly to that type of governor wherein the centrifugal and inertia efforts of the weights are utilized to secure isochronous regulation.

The object of my invention is to provide a governor of this type which may be readily adjusted to any required degree of isochronism and which shall be rendered more stable and at the same time more quick to respond to variations in load, being both sensitive and certain in action.

To this end my invention consists in concentrating the centrifugal and inertia weights about common centers of gravity and so connecting the centripetal springs to the weight-arms that the moments of the efforts of the springs shall be made to increase as the weights approach the center of rotation, and vice versa, and also in so locating the weights with reference to their centers of suspension and the center of rotation that the components of centrifugal force perpendicular to lines drawn through the center of suspension and the center of gravity of the weights in their several positions will increase as the weights pass from their minimum to their maximum extensions.

My governor also differs from those of ordinary construction in that the relation subsisting between the centrifugal and inertia efforts is such that the centrifugal effort unaided by that of the inertia is sufficient to overcome the resistance of the springs and working parts at normal speed and the effort of inertia becomes operative only when there is a tendency to depart from that speed,

at which time the inertia supplements the centrifugal effort.

In the usual construction of inertia governors the centrifugal and inertia weights are separate and either integrally united or connected one with the other by links. Where the two weights are thus connected, the inertia weight is so positioned relative to the center of suspension that the centrifugal effort of the weight will be absorbed by the suspension-pin, and it is held to be inoperative centrifugally as regards the centrifugal weight. As a matter of fact this is not so, since the two weights being connected together the centrifugal effort of the mass will act at the center of gravity of the combined parts, which is located somewhere on a line joining the centers of gravity of the two weights and at a distance from the center of gravity of the centrifugal weight inversely proportional to the two weights. The centrifugal effort of the mass then is greater or less than that of the centrifugal weight alone, according as the center of gravity of the mass is at a greater or less distance from the center of rotation than the center of gravity of the centrifugal weight. If the two weights be concentrated in one, then the centrifugal effort will be determined by the position of the center of gravity of but one weight undisturbed by any supplemental weight, while the inertia effort will be the same as before for equal radii. In carrying out my invention the center of gravity of the weight should be so located with reference to the centers of suspension and rotation that the component of the centrifugal effort tending to cause rotation about the center of suspension shall be at a maximum at the extreme outward position of the weight. With a single weight and spring the system will fulfil the conditions of my invention, but will be out of gravity balance. To obviate this difficulty, another weight of the same mass and same moment of inertia is therefore introduced and connected to the first by a link or links so positioned that the center of gravity of the entire system will be located at the center of rotation, or approximately so, in order that gravity balance will be established in all positions of the weights. In this construction the centrifugal and inertia efforts

have the same lever-arms, the latter always supplementing the former when there is a departure from normal speed and the former alone being operative when the speed is normal. The point of attachment of the springs and the direction of their efforts are also of the first importance. In the usual construction the direction of the efforts of the springs is in lines tangent to the arcs of rotation of the points of attachment about the center of suspension when the system is in mid-position. By advancing the points where the springs are attached to the rim of the wheel or governor casing in the direction of rotation and by giving the springs proper initial tension, which is dependent upon their extension, the moments of the efforts of the springs may be made to increase as the weights move toward the center of rotation, due to an increase in the load or any other tendency to reduced speed. By thus adjusting the points of spring attachment the governor will be caused to respond more quickly to changes of speed, and the engine may even be made to run faster with a load than without, or the adjustment may be such as to maintain constant speed up to the full capacity of the engine.

I attain the object of my invention by the construction and arrangement of the several parts of the governor, as illustrated in the accompanying drawings, in which—

Figure 1 is a vertical section, and Fig. 2 a side elevation, of my governor; and Fig. 3, a diagram illustrating the principles under which the governor operates.

Similar letters refer to like parts in the several views.

A represents the engine-shaft or the auxiliary shaft to which the fly-wheel or governor casing B is attached.

C and I are the governor-weights, hung by suitable arms to the suspension-pins D and J, respectively, which are spaced a suitable distance from the center of rotation A. The arm of the weight C also carries the pin E or an eccentric, to which the valve connection is coupled and which is made to approach or recede from the center A, according to the position of the weight C, thereby regulating the stroke of the valve. The centripetal spring G for the weight C is attached at one end to a pin F, secured to the arm of the weight, and at the other end to a hanger H, fastened to the rim of the casing B. It will be noticed that the angle which the radius D F makes with the medial line F H of the spring is an acute angle and that as the weight C is thrown out this angle will become more acute. To the arm of the weight I at K is attached a similar centripetal spring L, the other end of which is fastened to the hanger M, and the two weights are connected by the link N, coupled thereto at the points O and P. If we leave out of consideration the link N and its connections to the weights C and I and the valve-rod pin E, it will be seen that

the two weights and their arms if equal in other respects will balance each other on opposite sides of the shaft A and that the center of gravity of the system will lie midway in the line connecting the centers of gravity of the weights C and I or at the center of rotation. The unbalancing of the system by reason of the link N and pin E may be provided for by suitably proportioning weights C and I or by the use of a second link between the weights in a diametrically opposite position to that of link N. However, the weights of these unbalancing parts will be so little in comparison with the weights C and I that they may be left out of consideration, and the center of gravity of the system will be approximately at the center of rotation and will remain in that position no matter what may be the extension of the weights due to centrifugal force. The direction of rotation of the governor is indicated by the arrow in Fig. 2, and the weights are hung with their arms inclined in the direction of rotation, whereby the inertia effect of the weights will supplement their centrifugal efforts.

The principles governing the action of a governor arranged and coupled together as above described will be understood more clearly by reference to the diagram shown in Fig. 3. In this diagram, A represents the center of rotation of the system, and D the center of suspension of the weight C. As the system revolves the centrifugal force or effort of the weight C at any given position will be in the direction of the line A a, passing through the center of rotation and the center of gravity of the weight, and if we lay off on this line extended a distance a b equal to the unit of centrifugal effort and drop from the point b to the radius D a extended the line b c perpendicular thereto this line will represent the component of the centrifugal effort which is expended in rotating the weight C about its center of suspension D, and the ratio of a b to b c will represent the ratio of the actual centrifugal effort at any position of the weight C to its vertical component at that position. As the centrifugal effort can be readily calculated for any position of the weight, this perpendicular component may also be found for any position, and the force exerted by the weight at the point of attachment of the centripetal spring may be readily calculated, and from this the required initial tension and extension of the spring may be found for any given point of attachment.

As the weight C is revolved about the center D the angle between the radii D a and A a will gradually increase until the weight is in the position C', where the radii become equal, forming an isosceles triangle A D a', after which the angle between the radii will again decrease, as shown, when the weight is in the position C''. If the lines a b, a' b', a'' b'' are laid off equal to a unit of centrifugal effort, then b c, b' c', b'' c'' will represent the vertical components of the force corre-

sponding to these positions of the weight, and it will be apparent that the ratio of $a b$ to $b c$ will increase from the position C to C' and will decrease from the position C' to C" and that therefore the vertical components of the centrifugal effort will increase from the position C to the position C' and decrease if the weight is allowed to pass beyond the position C'. As it is essential for the operation of my 5 governor that this vertical component shall increase as the weight passes from its retracted to its extended positions, it is evident that the parts should be so arranged for the best results that the weight will not pass beyond the position C'. In fact, if C represents the position of the weight at its retracted position the extended position of the weight as my governor is arranged will fall somewhat short of the position C'. 10 Now if d represents the lever-arm of the centripetal effort of the spring G about the center D when the weight is in the position C the diagram furthermore shows that if the weight is revolved to the position C' the point 15 of attachment F will pass to the position F', in which position the lever-arm of the spring will be represented by d' , from which it becomes apparent that as the weight passes from its retracted to its extended positions 20 there will be a constant decrease in the moment of the spring, due to this decrease in leverage. It will also be apparent that by moving the point of attachment of the spring to the hanger H to the right or left the moment of 25 the spring about the center D may be diminished or increased, respectively, so as to bring the spring and weight to the proper degree of correlative adjustment for the proper operation of the governor, and the governor 30 may be so adjusted that the variation in the speed of the engine shall not exceed one per cent. within the rated capacity of the engine.

If X equals initial tension of the springs, S equals the scale of the spring, E equals the 35 extension of the spring corresponding to the movement of the weight from minimum to maximum position, and d and d' equals the lever-arms of the spring at minimum and maximum positions, respectively, then SdX 40 equals moment of the spring at minimum position of the weight and $Sd'(X+E)$ equals moment at maximum position. If SdX is greater than $Sd'(X+E)$, the speed of the engine will tend to increase with the application of load, since the spring will act more 45 strongly as the weight moves in, thereby causing the valve to be set more quickly and to admit more steam than if the system is in perfect equilibrium. If SdX is less than $Sd'(X+E)$, then the governor will be sluggish and the speed of the engine will be reduced as the load is applied. By solving for X we have $X > \frac{d'E}{d-d'}$. The initial tension therefore is a function of the extension. The usual practice is to make the initial tension sufficient to overcome the resistance of the

working parts, disregarding its relation to the extension. To give quick action and avoid unstable equilibrium, I use the formula $X > \frac{d'E}{d-d'}$ in determining the initial tension, making the excess, however, as slight as possible to answer the purpose, and I am enabled to do this readily by reason of the decreasing lever-arm of the spring.

Without going into a mathematical demonstration, which would only necessitate the recital of formulas well known and understood by those skilled in the art to which this invention appertains, it may be sufficient to state that the governor weights and springs and their correlative positions must be so proportioned and arranged as to comply with the following conditions: First, the moments of the weights as regards the points of spring attachment must be greater at their maximum than at their minimum extension; second, the difference between the sums of the moments of the efforts of inertia and centrifugal forces in the weights as applied to the points of spring attachment at maximum and minimum positions must be greater than the difference between the turning moments of the springs with reference to the points of suspension for the same positions. The effort of the springs will then be greater than that of the weights when there is a tendency to reduced motion by reason of increased load and less than that of the weights when the load is decreased. These moments when the speed changes are modified by the inertia of the weights, which tends to give uniformity of motion at any given speed. Theoretically the excess of springs over weights 105 to effect the opening of the valve should approximate zero for isochronous regulation; but as this would mean unstable equilibrium the excess should be as small as possible and yet prevent racing. If necessary, this excess 110 may be increased by advancing the point of spring attachment to the rim of the wheel in the direction of rotation—that is to say, to the right in the figures—or decreased by moving it in the opposite direction.

By proportioning and ascertaining the weights, spring tensions, and points of attachment in the manner above described by means of well-known formulas based on the weight and spring moments and equating the 120 centrifugal and centripetal moments so derived to the end that said moments shall be in equilibrium at all times, making, however, due allowance for the frictional resistance of the valve-gear, (and I believe that I am the first to utilize the theory of moments to this end,) I am enabled readily to design a governor for any given engine which will be positive in action for every change of speed and which will be susceptible of much finer adjustment than any governor with which I am acquainted. Moreover, I do away entirely with dash-pots, friction devices, and the like now made use of in overcoming the oversen-

sitiveness in this type of governor, and I can even do away with the usual governor-stops.

Having thus described my improvements, what I claim as my invention, and desire to secure by Letters Patent, is—

1. A centrifugal governor of the type described comprising a rotatable body, a weight carried by an arm pivoted upon said body at a point eccentric to the center of rotation, said arm being inclined from the line joining the centers of rotation and suspension in the direction of rotation and at an angle thereto which never exceeds ninety degrees, means whereby said arm will actuate the valve-gear, and a centripetal spring attached at one end to said body toward the periphery thereof and extending thence between the center of gravity of the weight and the centers of rotation and suspension to a coupling-pin on the arm, the radius from the center of which pin to the center of suspension makes an angle with the line of spring action which never exceeds ninety degrees and an angle with the line joining the centers of rotation and suspension which is always in excess of ninety degrees.

2. A centrifugal governor of the type described comprising a rotatable body, a weight carried by an arm pivoted upon said body at a point eccentric to the center of rotation, said arm being hung with reference to the direction of rotation, whereby the inertia of the weight will supplement the centrifugal effort of the weight in effecting changes in the position thereof, means whereby said arm will actuate the valve-gear, and a centripetal spring having one end attached to said body toward the periphery thereof and the other end coupled to the weight-arm at a point the radius from which to the center of suspension of said arm makes an angle with the line of spring action which never exceeds ninety degrees in any position of the arm and spring and an angle with the line joining the centers of rotation and suspension which is always in excess of ninety degrees.

3. A centrifugal governor of the type described comprising a rotatable body, a weight carried by an arm pivoted upon said body at a point eccentric to the center of rotation, said arm being hung with reference to the direction of rotation, whereby the inertia of the weight will supplement the centrifugal effort of the weight in effecting changes in the position thereof, means whereby said arm will actuate the valve-gear, and a centripetal spring having one end attached to said body toward the periphery thereof and the other end coupled to the weight-arm at a point the radius from which to the center of suspension of said arm makes an angle with the line of spring action which never exceeds ninety degrees in any position of the arm and spring, said spring being given an initial tension and extension whereby the moments of the spring efforts with reference to said center of suspension are made to increase, and said weight-

arm being positioned at an angle to the line joining the centers of suspension and rotation whereby the components of centrifugal force tending to produce rotation of the weight about said center of suspension are made to decrease, as the load on the engine increases, and vice versa.

4. A centrifugal governor of the type described comprising a rotatable body, a weight carried by an arm pivoted upon said body at a point eccentric to the center of rotation, said arm being hung with reference to the direction of rotation, whereby the inertia of the weight will supplement the centrifugal effort of the weight in effecting changes in the position thereof, means whereby said arm will actuate the valve-gear, and a centripetal spring having one end attached to said body toward the periphery thereof and the other end coupled to the weight-arm at a point the radius from which to the center of suspension of said arm makes an angle with the line of spring action which never exceeds ninety degrees in any position of the arm and spring, said spring being given an initial tension which is approximately equal to, or greater than, the product of the lever-arm of the spring, with reference to said center of suspension at the maximum extension of the spring, into the extension of the spring divided by the difference between the lever-arms of the spring at minimum and maximum extension, whereby the moments of the spring efforts with reference to said center of suspension are made to increase as the load on the engine increases, and vice versa.

5. A centrifugal governor of the type described comprising a rotatable body, a weight carried by an arm pivoted upon said body at a point eccentric to the center of rotation, said arm being hung with reference to the direction of rotation, whereby the inertia of the weight will supplement the centrifugal effort of the weight in effecting changes in the position thereof, means whereby said arm will actuate the valve-gear, and a centripetal spring having one end attached to said body toward the periphery thereof and the other end coupled to the weight-arm at a point the radius from which to the center of suspension of said arm makes an angle with the line of spring action which never exceeds ninety degrees in any position of the arm and spring, said spring being given an initial tension which is approximately equal to, or greater than, the product of the lever-arm of the spring, with reference to said center of suspension at the maximum extension of the spring, into the extension of the spring divided by the difference between the lever-arms of the spring at minimum and maximum extension, and said weight-arm being positioned at an angle to the line joining the centers of suspension and rotation which also never exceeds ninety degrees, whereby the difference between the moments of the spring efforts at minimum and maximum extension

is made equal to, or less than the difference between the combined moments of the centrifugal and inertia efforts of the weight with reference to said center of suspension at the maximum and minimum positions of said weight, substantially as and for the purpose set forth.

In testimony whereof I have affixed my signature in presence of two witnesses.
